[57] CLAIM

The ornamental design for a retrograde cardioplegia stylet, as shown.

DESCRIPTION

FIG. 1 is a perspective view of a retrograde cardioplegia stylet showing our new design;

FIG. 2 is a front elevational view thereof;

FIG. 3 is a rear elevational view thereof;

FIG. 4 is a top plan view thereof;

FIG. 5 is a right side elevational view thereof;

FIG. 6 is a bottom plan view thereof; and,

FIG. 7 is a left side elevational view thereof.

FIG. 1

FIG. 2

FIG. 3

FIG. 4

FIG. 5

UNITED STATES PATENT AND TRADEMARK OFFICE
CERTIFICATE OF CORRECTION

PATENT NO. : Des. 335,705

DATED : May 18, 1993

INVENTOR(S) : GERALD D. BUCKBERG et al.

It is certified that error appears in the above-identified patent and that said Letters Patent is hereby corrected as shown below:

Title page, Item [22] after "Filed: Jun. 4, 1991" insert
the following:

Prior Application

This design application claims priority to United States Patent Application Serial No. 07/187,230 filed April 28, 1988, which issued as United States Patent No. 5,021,045 on June 4, 1991, entitled "Retrograde Venous Cardioplegia Catheters and Methods of Use and Manufacture" naming as inventors Gerald D. Buckberg, M.D. and Robert J. Todd.

Signed and Sealed this

Twenty-fourth Day of May, 1994

Attest:

BRUCE LEHMAN
